UNITED STATES PATENT OFFICE.

ARIE JAN SCHIPPER, OF ALKMAAR, NETHERLANDS.

HOISTING-MACHINE.

1,317,322.

Specification of Letters Patent. Patented Sept. 30, 1919.

Application filed June 1, 1918. Serial No. 237,838.

To all whom it may concern:

Be it known that I, ARIE JAN SCHIPPER, subject of the Queen of the Netherlands, residing at Alkmaar, Kingdom of the 5 Netherlands, have invented certain new and useful Improvements in Hoisting-Machines, of which the following is a specification.

In gins which operate with friction cones there is, as is well known, the disadvantage 10 that in consequence of the friction of the elements there occurs a disadvantageous evolution of heat. This evolution of heat frequently increases to such an extent that after a certain time, for example after several 15 hours, the gin has, in consequence of its parts running hot, to be put out of operation until it has cooled down.

The means generally employed, of allowing the parts exposed to excessive friction 20 and heat evolution to run in an oil bath in order to lessen the friction coefficient, have not, so far as I am aware, yet been employed in gins for the reason that the friction surface would have to be increased in 25 proportion to the reduction of the friction coefficient. Consequently very large dimensions as regards the size of the friction cone would thus be necessary.

The present invention seeks to overcome 30 these known disadvantages by dispensing with the employment of friction cones for the purpose.

The characteristic features of the present invention reside in the fact that the frictional action on the winding drum necessary 35 for the operation of the gin is effected by means of a lamellar clutch, and in order to lessen the heat which arises, the winding drum is constructed in such a manner that it constitutes besides a housing for the lamellar clutch, an oil bath in which the same 40 is immersed.

The employment of lamellar clutches is in itself known, but their employment in 45 gins as a substitute for the friction cones, so far as I am aware, has not heretofore been adopted.

The technical improvements which are attained by the foregoing arrangement may 50 be summarized as follows:

- (1) that a gin of relatively small dimensions is sufficient to raise comparatively heavy loads;
- (2) that such a gin may be kept in operation 55 the whole day without showing any re-

markable heating, and therefore without it being necessary to put it out of operation.

In the accompanying drawing is illustrated, in vertical section and by way of example, a gin constructed in accordance 60 with the present invention, in which 1 is the driving shaft and 3 is the stationary shaft. 2 is the winding drum which is mounted in a slidable manner on the two shafts 1 and 3 so that it can be moved backward and forward longitudinally in either direction by means of the lever 4, which is pivoted near its middle at 15, the upper part of the lever being broken away, as not needing illustration. 5 is a ring secured to 70 the driving shaft 1, and on this ring rest the lower lamellar plates 6 of the lamellar clutch *a* arranged on the driving axle, and on the rotation of the ring 5 they are carried around therewith. 7 indicate those lamellar or plate elements of the lamellar clutch *a* which are secured to the inner surface of the winding drum 2 and which on the rotation of the winding drum are carried around therewith. The lower lamellæ 6 and the 80 upper lamellæ 7 are arranged opposite one another alternately in the known manner in order that they may be able to follow, in the interior of the space formed by the ring 5 and the winding drum 2, the movement of 85 the winding drum to right or left when the latter executes its movement in either direction. On the fixed shaft 3 is likewise mounted a ring 8 which for its part serves to carry the lower parts 9 of a second lamellar clutch *b* which are arranged opposite the upper lamellæ 10 of the lamellar clutch *b*, and which upper lamellæ 10 likewise are attached to the inner surface of the winding drum 2. The lamellæ 9 and 10 of the 90 second clutch *b* are, in the same way as the lamellæ 6 and 7 of the other clutch *a*, capable of being slid to right or left in the direction of movement of the winding drum 2 and likewise follow the movement of the 95 latter.

The system therefore works simultaneously with two lamellar clutches *a* and *b* which are arranged symmetrically in the interior of the winding housing.

The winding drum is provided on each of its opposite sides with lips or thrust rings 11 and 12 facing toward the interior of the drum, which lips follow the backward and forward movement of the winding drum 110

produced by the lever 4. In either of the two end positions of the winding drum 2 the lips or rings 11 and 12 act on the respective clutches. In the extreme left-hand position 5 of the winding drum the lip or ring 11 presses on the lamellar clutch *a*, presses the lamellæ together, and causes the winding drum to be carried around by the rotating shaft 1. At the extreme right-hand position 10 of the winding drum 2 the lip or ring 12 engages with the clutch *b*, presses it together and causes the winding drum to be clutched to the stationary shaft 3.

In the event of the winding drum being 15 clutched to the rotating shaft 1, the whole gin is set in rotation and the load can be subjected to the raising or lowering action. In the other event, when the winding drum is connected with the stationary shaft 3, the 20 gin is out of action in spite of the continued rotary motion of the driving shaft 1.

In the central position of the system, that is to say when neither of the lips or rings 11 and 12 engage with either of the two 25 clutches *a* and *b*, the winding drum is able to rotate loosely for the purpose of the possible reversal of the system, in order for example to bring the load from the raising to the lowering position.

30 The space 13 formed on the one side by the winding drum 2 and the rings 5, 5, and on the other side by the housing 2 and the rings 8, 8 serves for the reception of the oil bath for the lamellar clutch. 14 indicates a dead 35 space which the rings 5 and 8 form one with the other.

Having now particularly described and ascertained the nature of my said invention, and in what manner the same is to be performed, I declare that what I claim is:

40 1. In hoisting mechanism, in combination with a pair of shafts arranged in alinement, a drum movable endwise over said shafts and shiftable for clutching and braking engagement, outwardly extending parallel lamellæ arranged at intervals in two series carried respectively by the proximate ends of said shafts, two series of lamellæ arranged in the inner face of said drum to alternate with the lamellæ of the rings, and means carried by said drum for forcing one 45 or the other of these series of lamellæ car-

ried by the drum into operative contact with the proximate series of lamellæ carried by the shafts. 55

2. In hoisting mechanism, in combination with a pair of shafts arranged in alinement, a drum movable endwise over said shafts, rings on the proximate ends of said shafts, outwardly extending parallel lamellæ arranged on said rings in series at intervals, two series of lamellæ arranged on the inner face of said drum to alternate with the lamellæ of the rings, and means carried by said drum for forcing one or the other of these 60 series of lamellæ carried by the drum into operative contact with the proximate series of lamellæ on one of the rings according to the direction of endwise movement of said drum. 70

3. A driving shaft and a fixed shaft each provided with a ring fast on said shaft, in combination with a drum movable endwise in either direction over the ends of said shafts and constructed to leave in all positions terminal space between said drum and at least one of said rings, and a pair of clutches within said drum, each consisting of two series of lamellæ and connecting said drum respectively with one of said shafts 75 or the other in the extreme endwise positions of said drum. 80

4. In hoisting mechanism, in combination with a pair of shafts arranged in alinement, a drum movable endwise over said 85 shafts, rings on the proximate ends of said shafts, outwardly extending parallel lamellæ arranged on said rings in series at intervals, two series of lamellæ arranged on the inner 90 face of said drum to alternate with the lamellæ of the rings, and means carried by said drum for forcing one or the other of these series of lamellæ carried by the drum into operative contact with the proximate series of lamellæ on one of the rings, according 95 to the direction of endwise movement of said drum, the latter being constructed to allow oil space between and about the lamellæ.

In testimony whereof I have affixed my signature in presence of two witnesses,

ARIE JAN SCHIPPER.
